UNITED STATES PATENT OFFICE.

JOHN G. GERBER, OF ROCHESTER, NEW YORK.

WELT FOR FOOTWEAR.

1,078,043.

Specification of Letters Patent. Patented Nov. 11, 1913.

Application filed April 29, 1913. Serial No. 764,335.

To all whom it may concern:

Be it known that I, JOHN G. GERBER, of Rochester, in the county of Monroe and State of New York, have invented a new and useful Improvement in Welts for Footwear, which improvement is fully set forth in the following specification and shown in the accompanying drawings.

The present invention relates to welts for foot wear and an object of the same is to provide a construction which is adapted to bend or turn about the shoe or boot without producing any bulging portions and, at the same time, to provide an unbroken edge.

To these and other ends the invention consists in certain parts and combinations of parts all of which will be hereinafter described, the novel features being pointed out in the appended claims.

In the drawings: Figure 1 shows a strip of leather from which the welt strips are cut; Fig. 2 shows the two strips after they have been cut; Fig. 3 is a section on the line *a—a* Fig. 2; Fig. 4 shows the welt bent or turned; Figs. 5 and 6 are enlarged views of opposite sides of one of the tongues; and Fig. 7 is an enlarged view of an edge of one of the tongues.

According to the present invention, a strip of leather 1 or other suitable material of uniform width is preferably provided and is cut on the line 2, Fig. 1, by any suitable means so as to provide the two strips 3 shown in Fig. 2. Each of the strips 3 has overlapping tongues along one edge. These tongues are of novel construction and permit the strip to be bent or turned to conform to the contour of the shoe or boot sole. Each tongue has its outer edge 4, narrower than its base, formed between the points 5 and 6. One side edge 7 of this tongue is perpendicular to the length of the welt, while the other side edge 8 is arranged at an oblique angle to the length of the welt 45 so that the side edges converge. One face of the tongue is provided with a beveled surface 9 which extends from the base of the tongue to the outer edge 4 thereof and is parallel with the edge 7, being as wide as the edge 4 is long. The other face of the tongue is beveled at 10 and this beveled portion extends from the outer edge 4 to the base of the tongue, is parallel with the side edge 8 and is substantially as wide as the outer edge 4 is long. With this arrange-

ment, both the beveled portions meet at the edge 4 making a knife or feather edge of the latter and causing the tongue to gradually increase in thickness from said edge to the base.

With a welt of this construction, when the latter is straightened out, a straight edge is provided along both sides as the ends of each outer edge 4 overlap slightly the adjacent tongues, yet each tongue is beveled on opposite sides in such a manner that the welt may be folded or bent to cause the tongues to overlap to a greater extent without producing any bulging. It is apparent that, during the bending, the tongues will overlap to a greater extent near their free ends and this overlapping decreases toward the bases of the tongues. It is for this reason that it is advantageous to have the thickness of the tongues decrease toward their free ends so that all bulging will be eliminated, thus doing away with the grinding away of the bulged portions.

What I claim as my invention and desire to secure by Letters Patent is:

1. A welt strip having tongues projecting from one edge thereof, said tongues decreasing in width toward their free ends and having opposite faces beveled near opposite edges and the beveled faces of each tongue overlapping the opposed beveled faces of proximate tongues to the free ends of the latter.

2. A welt strip having tongues projecting from one edge thereof, said tongues gradually decreasing in width and in thickness toward their free ends and each tongue overlapping the proximate tongues to the free ends of the latter.

3. A welt strip having tongues projecting from one edge thereof, each of said tongues decreasing in width toward its free end and having beveled portions on opposite faces, parallel with the opposite edges of the tongue and each tongue overlapping the proximate tongues to the free ends of the latter.

4. A welt strip having overlapping tongues projecting from one edge thereof, each of said tongues having an edge perpendicular to the length of the welt and an edge at an oblique angle to the length of the welt and each of said tongues being beveled on opposite faces parallel with the side edges.

5. A welt strip having overlapping tongues projecting from one edge thereof, each of said tongues having an edge perpendicular to the length of the welt and an edge at an oblique angle to the length of the welt and each of said tongues being beveled on opposite faces parallel with the side edges, the beveled portions being as wide as the outer or free edge of the tongue 10 so that the latter has a knife or feather edge.

6. A welt strip having overlapping tongues projecting from one edge thereof, said tongues gradually decreasing in width 15 and in thickness toward their free ends and being separated by V-shaped notches, the

apexes of which are at the bases of the tongues.

7. A welt strip having overlapping tongues projecting from one edge thereof, 20 each of said tongues decreasing in width toward its free end and having beveled portions on opposite sides parallel with the opposite faces of the tongue, the opposed beveled faces of proximate tongues converging to a meeting line located immediately at the bases of said tongues. 25

JOHN G. GERBER.
